United States Patent Office

Des. 228,578
Patented Oct. 9, 1973

228,578

CAMERA

Theodore J. Glaros, Roland L. Hron, and George E. Pribyl, Minneapolis, Minn., assignors to Cir-Tech, Inc., Columbia Heights, Minn.

Filed Aug. 16, 1972, Ser. No. 281,203

Term of patent 14 years

Int. Cl. D16—01

U.S. Cl. D61—1 B

FIG. 1

FIG. 2

FIG. 3

FIG. 4

FIG. 5

FIG. 1 is a front perspective view of a camera showing our new design;

FIG. 2 is a top plan view thereof, the bottom being plain and unornamented;

FIG. 3 is a left side elevational view thereof;

FIG. 4 is a front elevational view thereof;

FIG. 5 is a rear elevational view thereof.

We claim:

The ornamental design for a camera, as shown and described.
